[57] CLAIM

The ornamental design for a cable load sensor or similar article, as shown and described.

DESCRIPTION

FIG. 1 is a front and end perspective view of a cable load sensor or similar article showing my new design; FIG. 2 is a rear and opposite end perspective view thereof;

FIG. 3 is an end elevational view thereof;

FIG. 4 is a front elevational view thereof;

FIG. 5 is an elevational view of the end opposite to that shown in FIG. 3;

FIG. 6 is a rear elevational view thereof; and

FIGS. 7 and 8 are respectively top and bottom plan views thereof.

FIG. 1

FIG. 2

FIG. 3

FIG. 4

FIG. 5

FIG. 6

FIG. 7

FIG. 8
